(57) CLAIM

The ornamental design for packaging with surface ornamentation, as shown and described.

DESCRIPTION

FIG. 1 is a front elevational view of the packaging with surface ornamentation of the present invention;

FIG. 2 is an additional front elevational view thereof, shown in an alternate unclaimed environment,

FIG. 3 is an additional front elevational view thereof, shown in an alternate unclaimed environment,

FIG. 4 is an additional front elevational view thereof, shown in an alternate unclaimed environment,

FIG. 5 is an additional front elevational view thereof, shown in an alternate unclaimed environment,

FIG. 6 is an additional front elevational view thereof, shown in an alternate unclaimed environment; and,

FIG. 7 is an additional front elevational view thereof, shown in an alternate unclaimed environment.

The broken line showing of the packaging is included for the purpose of illustrating unclaimed environment and forms no part of the claimed design.
